UNITED STATES PATENT OFFICE.

ELMER W. UTZLER, OF PITTSBURG, PENNSYLVANIA, ASSIGNOR OF ONE-HALF TO JOHN H. CARLIN, OF PITTSBURG, PENNSYLVANIA.

COLLAPSIBLE CENTER.

No. 840,672.

Specification of Letters Patent.

Patented Jan. 8, 1907.

Application filed June 18, 1906. Serial No. 322,334.

To all whom it may concern:

Be it known that I, ELMER W. UTZLER, a citizen of the United States, residing at Pittsburgh, in the county of Allegheny and State of Pennsylvania, have invented certain new and useful Improvements in Collapsible Centers, of which the following is a specification, reference being had therein to the accompanying drawings.

- 10 My invention refers to improvements in center supports for sewers, conduits, tunnels, or any similar hollow structure composed of cement, concrete, brick, or other material built in continuous hollow form; and it has for its object to provide a simple, strong, and convenient means for providing a temporary supporting structure or pattern-framework upon and around which the desired construction is built.
- 20 The invention generally comprises two series of connected interfitting sections adapted to make abutting and overlapping contact longitudinally and transversely, respectively, and to provide a structure adapted for quick 25 and convenient assemblage and adjustment and of being as easily taken apart or removed from the finished structure.

Referring to the drawings, Figure 1 is a central vertical sectional view of a portion of the apparatus complete. Fig. 2 is a transverse sectional view on the line II--II of Fig. 1. Fig. 3 is a cross-section on the line III--III of Fig. 1 showing the cam-lock. Fig. 4 is a face view of the cam-lock of Fig. 3. Fig. 35 5 is a longitudinal section on the line V--V of Fig. 1 showing the cam-lock. Fig. 6 is a face view of the cam-lock of Fig. 5.

The sections composing the collapsible frame or "center" are of sheet-steel or iron, 40 wood, or other material arranged generally in an upper and a lower connected series composed of upper sections 2 and lower sections 3. These sections may be of any desired form in cross-section according to the cross-sectional area of the sewer or other conduit to be built and are bent into such form, as indicated in Fig. 2, or may be merely semi-circular or of other preferred shape. Each section 2 and 3 is provided at one end with 45 an inner plate 4, riveted to the end of the section and adapted to lap over, underneath, or within the next adjacent section, as clearly shown in Fig. 1, thus insuring an interfitting joint. Likewise one of the sections 2 or 3,

preferably the upper section 2, is provided 55 with an inner plate or flange 5, running along each meeting edge, sufficient clearness being left at each end for plates 4, whereby the sections 2 and 3 are thus neatly joined. For the purpose of clamping the sections together 60 endwise and of clamping the opposite meeting edges of sections 2 and 3, I employ an improved cam-locking mechanism. (Shown in the different figures and in detail.)

The endwise locking devices comprise the 65 arms or straps 6, which may be of wrought or malleable metal pivotally mounted at 7 between lugs 8 of a base 9, secured upon the edge of one of the sections, as section 2. In the outer end of arm 6 is pivotally mounted 70 at 10 a locking cam 11, adapted to bear by its variable radius periphery 12 against the face of lug 13, said lug having a terminal horn 14 and preferably provided with an undercut recess for the cam and projecting up from the 75 base 15, secured to the other meeting section 3. The cam 11 is provided with an operating-handle 16, of any suitable form or shape, preferably bent out for operating clearance, as shown, and by this construction it will be 80 seen that the strap 6 may be thrown around on its pivot 7 to locking position, as shown in Fig. 1, or out of the way when unlocked, as indicated in dotted lines in said figure.

When in locking position, the operation of 85 the cam bearing against lug 13 is to draw the opposite edge of the adjacent section tightly against the meeting edge of the section to which lug 13 is secured, in which position the parts will be rigidly held together until the 90 device is unlocked by reversing the cam. For the purpose of arresting the motion of the strap 6 I provide a bearing-lip 17, projecting inwardly from base 9, as shown, thus positively locating the operative position of 95 the cam.

The construction of the cam-lock for joining the meeting edges of sections 2 and 3 is generally similar to the construction just described, the parts being indicated by the 100 same numerals, primed, and the operation being likewise the same. In these locks, however, I provide the bearing-lugs 8' for the link with inwardly-projecting horn terminals 18, adapted to make abutting contact with the 105 horn terminal 14' of locking lug 13', while a supplemental bearing-lug 17' is adapted to make bearing-contact for the strap 6', thus in-

suring accurate bearing and positive engagement. A further important advantage of the horn 18 is that in making abutting contact with the opposite lug 13' or horn 14' the parts are so braced that any tendency of the meeting edges of the shell to buckle outwardly is positively prevented, while the edges of the sections are caused to accurately engage each other, preventing any overlapping disengagement. As shown in the drawings, the bases 9 and 9' are mounted upon the flange-strips 4 and 5, the parts being securely held together by rivets passing through the base, strip, and the outer shell, all rivets being preferably countersunk, so as to provide a smooth exterior surface. For distending or contracting the diameter of the sections in mounting or unmounting them and of positively holding the sections during the operation of building the surrounding conduit, I employ bracing elements of any suitable construction adapted for ready and convenient adjustment. For this purpose I have shown ordinary turnbuckles 19, engaging rods 20 25 20, said rods having terminal hooks 21 21 engaging corresponding apertures in inwardly-projecting lugs 22 22. As many such turnbuckles and attaching-lugs may be employed as are desired, depending upon the form of 30 the apparatus, its size, or other conditions. The bearing-lugs 22 may be of any suitable construction and may be conveniently made of strips of angle form riveted along the interior sides of the section, as shown in the 35 drawings, or these flange-lugs may be continuations of the strips 5 of the upper section or of single special lug form, as desired. An advantage of the cam-locking devices is that being attached to the sections they are always in position for use and not liable to loss or displacement, while being very strong and durable and capable of making a very secure 40 jointing connection between the sections.

The operation of the device will be readily 45 understood from the foregoing description. The sections are mounted in their assembled form, as shown in Fig. 2. The concrete or other structure is then built around the exterior, and when sufficiently hardened the interior center is collapsed, the locking cams first having been disengaged by drawing in the turnbuckle-braces of the upper section. This operation is indicated in dotted lines in Fig. 2, whereupon the upper sections may be 50 dropped down within the lower sections and removed endwise, after which the lower sections are drawn inwardly by the turnbuckle-braces and likewise removed.

The sections may be of any number, length, 60 or dimensions desired, and the invention may be changed or varied otherwise in different details of design or construction by the skilled mechanic; but all such changes and variations are to be considered as within the 65 scope of the following claims.

What I claim is—

1. A collapsible center consisting of interfitting sections of sheet metal, one of said sections having pivoted straps provided with locking cams, the other of said sections having holding-lugs adapted to be engaged thereby, whereby the adjacent edges of the sections may be drawn together and locked, substantially as set forth. 70
2. A collapsible center comprising interfitting sections of sheet metal having overlapping flanges, cam-actuated locking devices having pivoted cams with deflected operating-handles and adjustable bracing elements, substantially as set forth. 75
3. In a collapsible center, the combination with meeting sections, of pivoted straps provided with a locking cam, mounted on one section, and a lug on the adjacent section adapted to be engaged thereby, substantially as set forth. 80
4. In a collapsible center, the combination with meeting sections, of a base secured to one of the sections provided with pivotally-attached straps having a locking cam between their terminals, and an engaging lug secured to the other section adapted to be engaged by said cam, substantially as set forth. 90
5. In a collapsible center, the combination with meeting sections, of a base secured to one of the sections provided with pivotally-attached straps having a locking cam between their terminals, and an engaging lug secured to the other section and provided with a retaining-horn adapted to be engaged by said cam, substantially as set forth. 95
6. In a collapsible center, the combination with meeting sections, of a base secured to one of the sections provided with pivotally-attached straps having a locking cam between their terminals, and an engaging lug secured to the other section and provided with a retaining-horn and a cam-recess adapted to be engaged by said cam, substantially as set forth. 105
7. In a collapsible center, the combination with meeting sections, of a base secured to one of the sections provided with a pivotal bearing, a projecting bearing-lug, and pivotally-mounted straps having a locking cam pivotally mounted between their terminals, and a locking lug secured to the other section provided with a cam-engaging horn, substantially as set forth. 110
8. In a collapsible center, the combination with meeting sections, of an overlapping plate secured to the inner side of one of the sections and arranged to engage the inner edge of the next adjacent section, a pivotal bearing having a terminal horn secured to the first-named section and provided with pivotally-mounted straps carrying a pivoted cam between their terminals, and a locking lug secured to the other section having a 120
- 125
- 130

horned cam-engaging terminal, substantially as set forth.

9. In a collapsible center, the combination with meeting sections, provided with overlapping longitudinal and transverse inner flanges, locking lugs secured to the edges of some of the sections, and corresponding pivotally-mounted straps provided with locking cams secured to the edges of corresponding adjacent sections and adapted to engage said lugs, substantially as set forth.

10. A collapsible center comprising series of upper and lower longitudinally-interfiting sections, said upper and lower sections meeting in a horizontal plane and provided with engaging flanges, consisting of pivoted straps carrying cam-locking devices adapted to clamp the adjacent edges of said sections together, and collapsible bracing-rods se-

cured to and extending transversely from the opposite faces of said sections and provided with adjusting turnbuckles, substantially as set forth.

11. In a collapsible tubular structure of sheet metal, the combination of interfiting sections provided with longitudinal and transverse underlapping flanges, means for bracing and collapsing the sections, pivoted straps provided with locking cams, and corresponding engaging lugs secured to the meeting edges of said sections respectively, substantially as set forth.

In testimony whereof I affix my signature in presence of two witnesses.

ELMER W. UTZLER.
